UNITED STATES PATENT OFFICE.

PETER ROTH, OF NEW SALEM, NORTH DAKOTA.

FRUIT-JAR HOLDER.

1,273,096.

Specification of Letters Patent. Patented July 16, 1918.

Application filed July 18, 1917. Serial No. 181,346.

To all whom it may concern:

Be it known that I, PETER ROTH, a citizen of the United States, residing at New Salem, in the county of Morton and State of North Dakota, have invented new and useful Improvements in Fruit-Jar Holders, of which the following is a specification.

This invention relates to fruit jar holders and it consists in the novel features herein-
10 after described and claimed.

An object of the invention is to provide a holder of simple and durable structure which is adapted to securely retain a jar against turning during the operation of re-
15 moving the top or cover from the same, the parts being so arranged as to protect the hands of the operator by preventing them from being cut by coming in contact with the top while the same is being unscrewed
20 from the jar.

With this object in view the holder comprises a pliable metallic band adapted to be placed around the body of the jar, the said band being provided at its inner surface with
25 a rubber or elastic strip adapted to have contact with the surface of the jar whereby the band is held against slipping with relation to the same. Semi-cylindrical handles are attached to the ends of the band and the
30 ends of the said handles are connected with a U-shaped spring strip. Blocks are secured in the intermediate portions of the handles and are adapted to have contact with each other when the handles are brought together
35 thus preventing the said handles from being crushed or distorted when the device is in use.

In the accompanying drawing:—

Figure 1 is a perspective view of the
40 holder applied to a jar;

Fig. 2 is an edge elevation of the same.

Fig. 3 is a longitudinal sectional view of the same cut on the line 3—3 of Fig. 2.

The jar holder comprises a pliable band
45 1 of sheet metal which is adapted to be placed around the body of a jar. A strip 2 of rubber or similar material is attached to the inner surface of the band 1 and is adapted to have contact with the periphery
50 of the jar whereby the holder is prevented from slipping with relation to the jar when in operation. Semi-cylindrical handles 3 are attached at one end to the ends of the band 1 and normally converge toward each

other. The intermediate portions of the 55 handles 3 are filled with blocks 4 preferably of wood and the blocks are adapted to come in contact with each other when the device is in use thus preventing the handles from being crushed or distorted. The ends of 60 the handles 3 opposite those ends which are connected with the band 1 are connected together by means of resilient U-shaped metallic strips 5. The said strip 5 is under tension with a tendency to normally hold 65 the ends of the handles 3 which are connected with the band 1 spaced from each other.

In operation the band 1 is placed around the body of a jar and the handles 3 are 70 grasped and forced toward each other whereby the strip 2 is brought in frictional contact with the surface of the jar and the blocks 4 are brought together. Thus the jar is held against turning movement and the 75 operator using one hand for accomplishing this. With the other hand the operator may easily unscrew the top or cover from the jar without danger of cutting that hand which is holding the jar against turning 80 movement.

From the foregoing description taken in conjunction with the accompanying drawing, it will be seen that a jar holder of simple and durable structure is provided and that 85 the same may be conveniently used to advantage for holding a jar while removing the top or cover therefrom.

Having described the invention what is
90 claimed is:—

A jar holder comprising relatively rigid handles, a pliable metallic arcuate band attached at its ends to the handles at one end thereof, an arcuate resilient strip attached at its ends to the other ends of the handles, 95 the ends of the band being spaced apart for a greater distance than the ends of the strip whereby the handles normally converge toward each other from the band to the strip, the band being of greater diameter than the 100 strip, said band and strip serving as the only means which attach with the handles, thereby leaving an unobstructed space between the handles which leads at the ends of the handles into the spaces within the 105 band and the strip.

In testimony whereof I affix my signature.
PETER ROTH.
